ATTORNEY.

UNITED STATES PATENT OFFICE.

THOMAS L. McKEEN, OF NEW YORK, N. Y., ASSIGNOR TO THE TROJAN CAR COUPLER COMPANY, OF TROY, NEW YORK.

BUFFER-PLATFORM FOR CARS.

SPECIFICATION forming part of Letters Patent No. 575,971, dated January 26, 1897.

Application filed November 24, 1896. Serial No. 613,288. (No model.)

To all whom it may concern:

Be it known that I, THOMAS L. McKEEN, a citizen of the United States, residing at New York, in the county of New York and State 5 of New York, have invented certain new and useful Improvements in Buffer-Platforms for Cars; and I do hereby declare the following to be a full, clear, and exact description of the invention, such as will enable others skilled 10 in the art to which it appertains to make and use the same.

My invention relates to certain new and useful improvements in buffer-platforms for cars, and particularly to that class shown and 15 described in a joint application for Letters Patent filed by Alfred H. Renshaw and myself September 10, 1896, Serial No. 605,403.

My present invention has for its objects to provide righting-springs which shall assist in 20 restoring the buffer-platform to its normal position and at the same time perform the function of an "equalizer;" and with these ends in view my invention consists in providing brackets for the side buffer-stems, which shall 25 be limited in their rearward movement to constitute stops or abutments for the springs surrounding the stems, and having at the same time a capacity to move forward against springs which operate to restore the brackets 30 to their normal position and with them the side stems and buffer-platform, all as will be hereinafter more fully described.

In order that those skilled in the art may 35 fully understand my invention, I will proceed to describe the same, referring by letters to the accompanying drawings, in which—

Figure 1 represents a plan view, partly in 40 section, of a buffer-platform and connections embodying my invention. Fig. 2 is a plan view of a modification of the spring-actuating devices for restoring the brackets to their normal positions, and Fig. 3 is a similar view of another modification.

Similar letters of reference denote like parts 45 in the several figures of the drawings.

A represents the ordinary central longitudinal sills of the body or frame of a railroad-car as usually constructed, between which is located the central buffer-platform stem B.

50 The head or transverse beam, which consti-

tutes the support for the ordinary stationary platform, is shown at C; and D is the ordinary platform, projecting from and sliding within which is the auxiliary or buffer platform E; and F F are side buffer-stems pivotally connected at their front ends to the buffer-platform E, and J K represent exterior and interior coil-springs arranged around the stems F and between the collar G and shoulder H and the brackets a, all substantially as 55 shown and described in the pending application hereinbefore referred to; and in lieu of the auxiliary "righting-springs" shown in said application I employ brackets a, which constitute guides for the rear ends of the 60 buffer-stems F, which brackets are pivoted at b to a suitable lug c, secured to and projecting from the car-frame. These brackets a are each formed with a head d, bearing 65 against the lug-plate, as shown, and constitute a stop to limit the rearward movement of the bracket, and with a toe e, bearing against a flat spring f, interposed between the toe e and the lug-plate. The buffer-stems 70 F, after passing through suitable orifices in the brackets a, are secured in place by collars F' and pins G' or in any other desired manner.

From the construction shown it will be seen that when either end of the buffer-platform is forced backward in the act of coupling or 80 as a result of the cars traversing a curve the collars G and shoulders H bear against and compress the coil-springs J K, the brackets a being held rigid by the contact of its heel d with the lug-plate. The stem on the opposite 85 side is correspondingly pulled forward by the platform E, and as the collar F' and pin G' hold it within the bracket a the free end of the latter is pulled forward and, swinging on its pivot b, the toe e compresses the flat spring 90 f, and consequently when the conditions permit the platform E to resume its normal relation to the stationary platform D the coil-springs J K on one side and the flat spring f on the other side coöperate in their reacting 95 power to bring the buffer-platform to its normal position.

In Figs. 2 and 3 I have shown modifications as to the character and location of the springs employed to restore the brackets to their nor- 100

mal positions and at the same time the side stems and buffer-platform.

At Fig. 2, as will be seen, the plate which secures the lug *c* to the car-sill is provided with a stem *g*, adapted to center and support one end of a coil-spring *h*, used in lieu of the flat spring *f* shown at Fig. 1, and the toe *e* of the bracket is formed with a pocket *i* for the opposite end of the spring *h*, and it will be seen that as the toe *e* approaches the lug-plate the coil-spring will of necessity be compressed and by its reaction the bracket will be forced back to its normal position in substantially the manner already described as to the flat spring *f*.

At Fig. 3 I have shown the bracket substantially like that shown at Fig. 1, but with an eye or hook *j* at its free end, between which and any suitable cross beam or bar *k* is arranged an extension coil-spring *l*, which upon contraction will restore the several parts to their normal positions.

It will therefore be understood that I do not wish to limit myself to the exact character or location of the springs which perform the function of resisting the forward movement of the free end of the bracket *a* and restores the same to its normal position, and it will also be readily understood that the spring-brackets *a* not only subserve the purposes hereinbefore described, but that they also constitute what are known in the art as "equalizers," and in that class of devices dispense with the ordinary transverse connect-

ing yoke or bar between the rear ends of the 35 side buffer-stems.

From the construction shown it is obvious that the repair and substitution of parts may be readily made and that the structure as a whole is economic of construction and effective in operation.

Having described the construction, operation, and advantages of my improvement, what I claim as new, and desire to secure by Letters Patent, is—

1. In combination with the stationary platform, auxiliary buffer-platform and side buffer-stems pivoted to the buffer-platform as described, the equalizing-brackets *a* formed with heel *d* and pivoted to lugs *c*, and the 50 equalizing-springs for restoring the brackets to their normal positions, substantially as and for the purposes set forth.

2. In combination with the stationary platform, auxiliary platform and side buffer-stems 55 pivoted to the buffer-platform as described, the equalizer-brackets *a* formed with heel *d*, toe *e* and pocket *i*, and pivoted to the lugs *c*, and the coil-springs *h* interposed between the toe *e* and lug-plate, substantially as and for 60 the purposes set forth.

In testimony whereof I affix my signature in presence of two witnesses.

THOMAS L. McKEEN.
